UNITED STATES PATENT OFFICE.

KENNETH HOWIE, OF NORRISTOWN, AND WILLIAM O. TAYLOR, OF LIMERICK, PENNSYLVANIA, ASSIGNORS TO WILDMAN MFG. COMPANY, OF NORRISTOWN, PENNSYLVANIA, A CORPORATION OF PENNSYLVANIA.

STRIPING MECHANISM FOR KNITTING MACHINES.

Application filed April 3, 1922, Serial No. 549,253. Renewed July 8, 1924.

To all whom it may concern:

Be it known that we, KENNETH HOWIE and WILLIAM O. TAYLOR, citizens of the United States, and residents of Norristown 5 and Limerick, respectively, in the county of Montgomery and State of Pennsylvania, have invented certain new and useful Improvements in Striping Mechanism for Knitting Machines, of which the following 10 is a specification.

The invention concerns a circular multiple feed striping knitting machine having its feeds distributed at separated points about the needle circle.

15 The invention consists in the features and combination and arrangement of parts hereinafter described and particularly pointed out in the claims.

In the accompanying drawings

20 Figure 1 is a side view of a knitting machine embodying my invention.

Fig. 2 is a plan view of pattern mechanism for controlling the different feeds.

25 Fig. 3 is a vertical sectional view with parts in elevation.

Fig. 4 is detail view of a part of the pattern mechanism looking from the right of Fig. 3.

Fig. 5 is a view similar to Fig. 4 with 30 parts in section.

Fig. 6 is a vertical sectional view of the central head of the controlling connections.

Fig. 7 is a detail view of cutter means.

Fig. 8 is a plan view of the central head of 35 Fig. 6.

Fig. 8^a is a detail view of a star wheel and cam.

Fig. 9 is a plan view of the devices at one of the yarn feeds.

40 Fig. 10 is a plan view partly in section of certain of the devices at one of the yarn feeds.

Fig. 11 is a face view of the inner side of one of the sections of the needle cam ring.

45 Fig. 12 is a plan view of the section of the cam ring of Fig. 11 with certain devices associated therewith.

Fig. 13 is a plan view of the base ring

and rotary take-up ring with cams carried by the latter for giving movement to the 50 pattern mechanism and controlling connections.

In the drawings 1 indicates a part of the head of a knitting machine. This is supported from a base ring 2 by frame parts, 55 one of which is shown at 3, the machine being of the type in which the cam ring is fixed and the needle carrier rotates. 4 is the revolving take-up ring or plate, the take-up mechanism being omitted, as this forms 60 no part of the present invention. The invention is shown in connection with a latch needle machine, though it will be understood that it is equally applicable to a spring 65 beard needle knitting machine.

There may be any desired number of feeds, for instance, eight. One of the yarn guides is shown at 5, there being one of these guides at each feed and it will be understood that these feeds are equally spaced 70 about the knitting head. Any one or more of the feeds is rendered inoperative by retracting the needle advancing cam at that feed, so that the needles will not be advanced to take new yarn, and shed their 75 old loops below their latches, and hence no knitting will be done at this inoperative feed and the old loops will not be cast off. For retracting the needle advancing came from operative position, there is a star wheel 7 80 at each feed which is shifted into different substantially horizontal planes by a vertically movable support or bracket 8, Fig. 1 and Fig. 10 so that the upper and lower arms 7', 7'' of the star wheel will be located 85 either in or out of the path of a contact member or dog 9 travelling with the knitting head. Each star wheel 7 has two pairs of arms, one pair being in a higher plane than the other pair, and the arms of each 90 pair are diametrically opposite each other. The higher pair of arms are indicated at 7' and the lower pair at 7''.

When the bracket 8 is swung down the upper pair of arms will be in the same horizontal plane with the travelling dog 9, and

when the bracket 8 is swung to its upper limit the lower pair of arms 7' will be in the plane of said dog. The star wheel is fixed to a shaft or body 7^a rotatably mounted in the bracket 8 under frictional restraint of a spring pin 8^a. The lower end of the star wheel shaft or barrel is provided with a recess or socket 7^x receiving a cam member 6 consisting of a flat plate carried by a shaft 10 or barrel 6^x, rotatably mounted in a fixed bracket 6^a secured to the fixed cam ring. A detent 6^b serves to prevent overthrow of the cam and star wheel when the latter is struck and turned by the dog 9.

15 When the bracket 8 is depressed and the dog 9 strikes one of the high arms 7' of the star wheel, the cam 6 will be turned flatwise to a lever 10, pivoted in the cam ring at 11 and this lever will be free to swing 20 outwardly away from the center of the machine and allow the needle raising cam *a* to assume operative position. This cam is carried by an arm *b* pivoted at *c* to the cam ring and pressed by a spring *d* to operative 25 position. The cam is swung outwardly into inoperative position as shown in Fig. 12 dotted lines when the cam 6 is turned so that its edge forces the lever 10 inwardly. This lever 10 operates a pin *e* which bears on 30 the tail of the lever *b* carrying the needle advancing cam.

The star wheel 7 remains coupled up with the cam 6 by means of the forked construction at 7^x of its barrel, whether the bracket 35 8 be up or down and the arrangement is such that if the star wheel is struck by the dog 9 it will give a quarter turn to the cam 6 and this acting upon or relieving the lever 10, as the case may be, will shift the 40 needle advancing cam in or out to make it operative or inoperative upon the needles.

The pivoted bracket 8 has an arm 8' extending up therefrom upon whose laterally extending upper end 8'' a bell crank lever 45 14 bears, Figs. 1, 9 and 10. This bell crank lever is pivoted at 15 to the stationary sinker cam ring 16 of the knitting head.

The bell crank lever 14 is operated by a rod 17, Figs. 1, 6, 8 and 9, extending towards 50 the vertical axis of the knitting head. The rod is guided at its inner end in a part of a support or track ring 18, Fig. 6, forming part of a central head, which ring is held in fixed relation to the knitting head by a post 55 19 to which it is rigidly secured. This post is at the axial center of the knitting head, and it depends from a bracket or arm 20, extending up from the fixed base 21 of the knitting head.

60 In an eight feed machine, there will be eight of the radial rods 17 with their associated parts 6, 7, 8 and 14, together with the needle advancing cams, one for each feed.

The rods 17 are controlled as follows:

65 An oscillating ring 22, also forming a

part of the central head, Figs. 6 and 8, is mounted on the fixed track ring 18. It is held down and guided thereon by screws 18' held by the track ring 18 and having their heads overlapping the flange 22' of the oscillatory ring 22. This ring carries a series of devices to be selected by pattern mechanism and which in turn select connections for controlling the feeds, which devices in the example chosen to illustrate the invention consists of plates 23 pivotally mounted at 24, each having a dog or pawl 27. These traveling devices or plates are depressed by headed push pins 25, one for each plate, said pins being slidably guided in a head 25' fixed on the depending rod 19. When any one of the pins 25 is pushed downwardly it will force the corresponding plate 23 down from an inclined position shown at the left of Fig. 6 to the substantially horizontal position shown at the right of said figure. The raised or inclined position of the plates is the normal one. Each plate is pressed upwardly by a spring 23^x and is stopped by the head of a screw or post 26 which is seated in the plate 22 and extends up through an opening in the pivoted plate 23. When either plate is pressed down its pawl 27 will lie in the same horizontal plane with a tooth of a star wheel 28 and, by engaging said tooth, will give the star wheel a quarter turn, as a result of the movement of the back and forth or oscillating carrier ring 22 carrying the depressed plate with it, on its stroke 95 in the direction of the arrow X in Fig. 8.

The turning of the star wheel, which is mounted by its shaft 29 in the fixed track plate 18 and forms part of the power transmitting connection leading to the feed and now to be described, will turn a cam 30 fixedly mounted on the lower end of its shaft 29. This cam bears upon a pin 31 carried by an arm 32 pivoted at 33 to the underside of the plate 18. The end of arm 32 has a projection 33' to bear on the inner end of the rod 17, so that when the high part 30' of the cam 30 presses upon the pin 31 the arm 32 will be turned outwardly and the rod 17 will be moved radially outward, to cause the bell crank lever 14 to depress the arm or post 8' with pivoted bracket 8 against the tension of its spring 35 and the star wheel 7 will be lowered so that one of its upper arms will be in the path of the dog 9 carried by the rotating needle cylinder, and when the star wheel is turned in this lowered position the cam 6 will be turned to change the position of the needle advancing cam, that is, the cam 6 will be turned from its endwise position in relation to the lever 10 to its flatwise position relative thereto and the needle advancing cam will be set inwardly towards the machine center in position to operate the needles to knit.

This will effect a change at this particular 130

feed, and the parts will remain in this position until the next change is made, when the star wheel 28 at the central controlling mechanism will be given another quarter turn, thus turning the cam 30 to carry its high part 30' away from the pin 31 and bring its low part 30" opposite the pin which immediately moves into this low part under the pressure of the spring band 34 and this will cause the projection 33' to recede from the rod 17 and allow said rod to recede or move towards the axis of the head under pressure of spring 35 which lifts the bracket 8 and causes post 8' to rock the bell crank lever 14 inwardly or towards the center of the machine. The lifting of the swinging bracket 8 will also elevate the star wheel 7 with the result that this particular feed will be changed again (thrown out of operation) by the dog 9 operating upon the lower arm of the star wheel, which by the elevation of the star wheel, has been brought into the plane of travel of the dog. The cam 30 has depressions at its high and low parts and the pin 31 of the pivoted arm 32 falls into these notches and acts as a detent to prevent the cam from overthrowing. All of the said arms are under pressure of the spring band 34.

30 It will be seen that the step by step movement of the cam 30 operates the arm 32 to push the rod 17 radially outward or allows the arm to be retracted by the spring band 34 to allow the rod to move radially inward towards the center of the machine and at all times the arm acts to hold the cam 30 against overthrow.

One oscillation or back and forth movement of the ring 22 takes place at each revolution of the knitting head and therefore all of the pawl plates 23 perform a back and forth movement laterally in a horizontal plane for each revolution of the machine, and if any plate be depressed by its push pin, the companion star wheel 28 will be operated one step by the tooth of the plate contacting therewith. The member 22 is mechanically operated by a rod or rods 36, connected with a pin or pins 37, depending from the oscillating ring through a slot 38 in the fixed bracket or track ring 18, and carried by an arm 38' turnable about the post 19. The other ends of the rods are connected with an arm 39 fixed on a vertical rock shaft 40 suitably journaled in fixed frame parts and having an arm 41 fixed thereto at its lower end and extending under the take-up ring to be operated by a cam 42 secured by posts 43 to the under side of the rotating take-up ring 4. The oscillation of the ring 22 is comparatively short.

It will be seen from the above that the throwing in or out of the feeds results from the turning of the cams 30 which determines

the positions of the corresponding star wheels 7 up or down and that these star wheels are operated by the travelling dog 9 to change the position of the cam 6 and thus set the needle advancing cam *a* in or out.

Reverting to the adjustable needle advancing cam *a* it will be understood that this raises the needles to their upper limit for knitting after they have been partly raised by the fixed cam *f* indicated in dotted lines in Fig. 11. In other words if the cam *a* is set in towards the vertical axis of the machine the needles after being partly raised by the fixed cam *f* shown in dotted lines, will be further advanced by travelling up and over the cam *a* and will then thus take the yarn and knit, whereas if the cam *a* is set outwardly by the star wheel 7 and connections described, the needles will be raised only part way by the fixed cam *f*, but will pass the yarn feed without taking the yarn, and this "end" will be carried around and into a cutter 81, 81' which is operated at each revolution of the machine by a cam 90 on the arm 38' Fig. 6.

This cam depresses a rod 84 connected with the movable blade 81 of the cutter. A spring 82 opens the cutter when the cam 90 moves away from the rod 84. The loose end of the yarn will be caught and held by a spring clamp wire or loop 92, Fig. 9 against a plate 95 held by a bracket 94 fixed to the cam ring 16.

For depressing the pawl plates 23 in any prescribed order to make the striped pattern, a jacquard mechanism is employed operating mechanically and controlling the said plates by mechanical connections to the push pins 25.

These connections include flexible or spring rods 44 lying in tubes 45 which extend from the central head or block 25' at different points around the same to a bracket 46 in which they are supported. These spring rods or flexible operating means are preferably provided by closely coiling a wire, that is, it is like a coiled spring with its coils closed one upon another so that while it is free to accommodate itself to the curves of the tubes 45 it provides a substantially longitudinal rigidity capable of transmitting power imposed thereon. There is one of these tubes with its flexible rod for each feed and one for a counter operating rod, and their ends are arranged in line, side by side, in said bracket.

Push pins 25*, one for each tube depend therefrom and rest upon bell crank levers 47 pivoted to the bracket, so that when any one of the bell crank levers is operated it will push up the pin 25* resting thereon which will push the spring rod or band

85

130

44 through the tube, depress the push pin 25 at the other end of said tube and thus the corresponding pivoted plate 23 will be depressed to make its pawl 27 engage, and 5 by its movement along its arcuate path, turn the appropriate star wheel 28 and thus throw in or out that particular feed to which this operated train of connections belong.

10 The bell cranks 47 are operated by rods 48 having hooks 49 to be engaged by slideable pawl arms 50 having hooks 51 to engage the hooks 49. Normally the pawl arms 50 are in elevated position out of engagement with the hooked rods 48 as shown in Fig. 3. They are mounted pivotally on an actuating rod 52 slidably guided in the fixed forks 53, forming a part of the bracket 46, and they rest upon the heads at the 15 upper ends of feeler fingers or pins 54 slidably mounted in a carrier bar 55 supported by rods 56 slideably vertically of the depending tubular members 57 of the fixed bracket member 46'. This carrier bar 20 with its feeler pins is pressed normally upward by a spring 58, Fig. 1, hereinafter mentioned.

The feeler pins or fingers are adapted, when permitted to do so, to pass down 30 through openings in a fixed plate 60 Figs. 3, 4 and 5, of segmental form. They are lowered as a series by an arm 61 engaging a recess 62 in the carrier bar 55, and connected to a swinging frame 63 pivoted at 35 64 to the fixed bracket 46 and oscillated by an arm 65, Fig. 1 forming a part of the swinging frame, which arm is operated by a vertical rod 66, from a lever 67 pivoted in a bearing 68 on the fixed base ring 2.

40 The pivot for this lever 67 consists of a shaft mounted in the bearing 68 and having an arm 69, Fig. 2 provided with a roller 70 to be engaged by a cam rib or plate 71 mounted by arm 72 on the rotary take-up ring.

A spring 58 presses upwardly against a tail extension 73 of the lever 69 and through the connections just described keeps the carrier 55 of the feeler fingers 54 elevated. But 50 when the cam rib 71, Figs. 1 and 13 of the rotary take up plate works under the roller 70, the carrier 55 with the feeler fingers are lowered and some or all of them will pass through the jacquard member according 55 to the disposition of holes therein. This jacquard member consists of a sheet of suitable material such as heavy strong paper *g* passing over the discs 74 having teeth 75 engaging marginal perforation in 60 the endless jacquard member. The discs 74, Fig. 5 are joined together by a coupling 74^a secured to their hollow hubs 74^a and constitute a drum mounted rotatably upon pin 74^b fixed in the bracket 46.

65 The fixed perforated platform or seg-

mental support 60 for the jacquard band is supported by the hubs of the discs or drum structure 74 and it is held against turning by an arm 74^c, Figs. 3, 4 and 5 held in the bracket 46 and having a forked end 74^d 70 engaging a pin on a depending arm 60^x of said platform.

This jacquard drum is turned step by step to feed the jacquard member as will be hereinafter described. The jacquard member passes over the perforated segmental fixed plate 60 and if an opening or openings in the jacquard sheet registers with an opening in the segmental fixed plate the corresponding feeler pin or finger, when lowered by the carrier bar 55, will go down through the registered openings and consequently the corresponding pawl arm 50, which is resting on this pin, will fall into alignment with the hook of rod 48 and then as the pawl arm 50 slides back (as herein-after mentioned) it will pull upon the hooked rod 48, rock the corresponding bell crank 47, elevate its push pin 25^x and through the spring rod 44 in the tube 45 the appropriate push pin 25 will be thrust down and the corresponding pawl plate 23 will be lowered, carrying its pawl or tooth into the plane of the star wheel 28 belonging thereto so that upon the movement of the oscillating plate 22 the star wheel will be operated to throw the feed in or out as above described.

The backward movement of the pawl arms 50 takes place altogether and for doing this the actuating bar 52 is slid in its guideways by links 76 connected with the up-standing arms 63^x of the rocking frame 63. This backward sliding movement takes place simultaneously with the depression of the feeler carrier bar 55, both movements being derived from the same connections i. e. rocking frame 63, arm 65 thereof and the connections back to the roller 70. The feeler carrier bar is lowered by the arm 61 attached to the rocking frame 63 as before described. Some lost motion of the pawl arms 50 takes place, however, before they operate the hooked rods 48 because the hooks of these pawl arms are somewhat in advance of the hooks of the rods 48, as shown in Fig. 3.

If, however, any feeler finger or pin 54 strikes an imperforate part of the jacquard member which covers the hole in the segmental platform 60, it will be arrested while the carrier bar 55 continues its downward stroke and this arrested feeler finger will hold up its particular pawl bar 50 which is resting thereon so that it will not engage the hooked rod 48 as it travels rearward and consequently it will perform an idle sliding movement when the actuating rod 52 moves back, and the train of connections individual to this pawl arm and

feeler finger, leading to the pawl plate 23 will not be operated and thus this pawl plate will remain elevated and will not operate its star wheel 28, when the movement of the 5 oscillating plate 22 takes place.

For turning the jacquard drum a ratchet 77 is employed connected with the drum and engaged by a pawl 78 pivoted at 79* to an arm 79 pivoted at 80 to the bracket 46.

10 This depending arm has an adjustable stop screw 81* to bear against the bracket 46.

The arm 79 above its pivot is borne upon by a horizontal rod 81 pivoted at 82, Figs. 1 and 2 to the bracket 46 and operated by

15 a pin 83 on an arm 84 clamped by a screw 85 to the vertical rock shaft 40, Fig. 2.

The lever 79 bears upon a spring pin 86 working in the bracket. When the rock shaft 40 is turned in the arrow direction

20 Fig. 2 to give the member 22 a movement in the direction of the arrow α , for turning any one or a number of the star wheels 28, that the pattern calls for, the parts just described will be operated to ad-

25 vance the pawl 78 to engage a fresh tooth of the jacquard drum ratchet. This stroke of the pawl 78 will be its idle one, the jacquard drum not being turned on this movement, as it should not be, owing to the fact that

30 the feeler fingers have been lowered and one or more of them has passed through the hole or holes in the jacquard sheet, but on the reverse movement of the rock shaft 40

35 the spring pin 86 will operate the lever 79 and the pawl 78 will be given its movement to turn the ratchet and the jacquard member one step, the feeler pins all being raised at this time.

As above stated the invention can be car-

40 ried out in connection with a spring beard needle knitting machine, and for this purpose substantially the same pattern mechanism would be used together with the central head carrying the pawl plates 23 and

45 the connections leading from this head to the various feeds would be the same. The main difference over the present organization would be that instead of controlling the needle advancing cam from the rotation

50 of the star wheel 7, the needle presser cam and shiftable yarn fingers would be controlled in a manner like that disclosed in our application for Letters Patent of the United

55 States #409,265 filed September 9, 1920, and 426,564 filed Nov. 26, 1920.

It will be understood further that the mechanism herein shown and described is illustrative of one embodiment of our invention and is not to be regarded as restrictive upon the invention the scope of which is defined by the appended claims.

It will be observed that we employ controlling mechanism for the several feeds disposed coaxially of the knitting head and comprising a mechanically operated mem-

ber, as 22, and power transmitting devices as 23, carried by said travelling member 22 and that this controlling mechanism is in turn controlled by the pattern mechanism, and while the devices 23 are selected by the 70 pattern mechanism they form as a group selecting mechanism in respect to the connections leading to the feeds, the whole group having travelling movement and the selection of the appropriate connection being 75 due to the setting of the member 23 belonging thereto into line so as to contact therewith.

The pattern mechanism shown herein will be made the subject of a divisional applica- 80

We claim:

1. In combination in a circular knitting machine, a plurality of feeds disposed at separated points about the same and each including knitting devices, a central head having selecting devices, one for each feed for determining which feed will be changed to knit or not knit, pattern mechanism controlling the setting of the devices in selecting position in a prescribed order, connections, one for each selecting device, to be hit or missed thereby extending from the selecting devices to their respective feeds to control the knitting and power operated 90 connections for moving the selecting devices, when set by the pattern mechanism, to drive the selected connections leading to the feeds, all the needles passing an idle feed simply holding their loops without performing their knitting actions, substantially as described.

2. In combination in a circular knitting machine, a plurality of feeds disposed at separated points about the same and each including knitting devices, pattern mechanism, selecting devices controlled by the pattern mechanism for determining at which of the feeds knitting will or will not be done, power connections for driving the selecting devices and connections operated by the driven selecting devices when the latter are set in position to contact therewith for making the changes in the knitting conditions at the feeds, said selecting devices 105 being interposed between the power connections first mentioned and the connections leading to the feeds, all the needles passing an idle feed simply holding their loops without performing their knitting actions, 110

115 being interposed between the power connections first mentioned and the connections leading to the feeds, all the needles passing an idle feed simply holding their loops without performing their knitting actions, 120 substantially as described.

3. In combination in a knitting machine, a plurality of feeds disposed at separated points about the same and each including knitting devices, pattern mechanism, selecting devices controlled by the said pattern

125 mechanism to determine the changes at the feeds, to knit or not to knit, a carrier for the selecting devices having travelling movement, means for driving said carrier, 130

connections leading to the several feeds for changing the same to knit or not to knit, said connections being operable by the said travelling selecting devices when the latter are set in selecting position by the pattern mechanism, and being missed by said travelling devices when set out of selecting position, substantially as described.

4. In combination in a knitting machine, 10 a plurality of feeds disposed at separated points about the same and each including knitting devices, pattern mechanism, selecting devices controlled by the said pattern mechanism to determine the changes at the 15 feeds, to knit or not to knit, a carrier for the selecting devices having travelling movement, means for driving said carrier, connections leading to the several feeds for changing the same to knit or not to knit, 20 said connections being operable by the travelling selecting devices when the latter are set in selecting position by the pattern mechanism, and being missed by said devices when the latter are not in selecting 25 position the travelling movement of said carrier being back and forth, substantially as described.

5. In combination in a knitting machine, 30 a plurality of feeds disposed at separated points about the same and each including knitting devices, pattern mechanism, selecting devices controlled by the said pattern mechanism to determine the changes at the feeds, to knit or not to knit, a carrier for the 35 selecting devices having travelling movement, means for driving said carrier, connections leading to the several feeds for changing the same to knit or not to knit, 40 said connections being operable by the travelling selecting devices when the latter are set in selecting position by the pattern mechanism and being missed by said devices when the latter are not in selecting position the travelling movement of said carrier being oscillatory about an axis, substantially 45 as described.

6. In combination in a knitting machine, 50 a plurality of feeds disposed at separated points about the same and each including knitting devices, pattern mechanism, selecting devices controlled by the said pattern mechanism to determine the changes at the feeds, to knit or not to knit, a carrier for the selecting devices, having travelling movement, means for driving said carrier, connections leading to the several feeds for changing the same to knit or not to knit, 55 said connections being operable by the travelling selecting devices when the latter are set in selecting position by the pattern mechanism, and being missed by said devices when the latter are not in selecting position said carrier being arranged coaxially with the knitting head, with the selecting devices disposed at different points about the same, the 60

travelling movement of the carrier being oscillatory about said axis, substantially as described.

7. In combination in a circular knitting machine, a plurality of feeds each including 70 knitting devices thereat, a plurality of selecting devices, one for each feed, each consisting of a member pivotally mounted to swing in a vertical plane, a carrier for the selecting devices, means for moving the carrier, pattern mechanism, means controlled thereby for setting the selecting devices in prescribed positions, and connections operated by the selecting devices as moved by the carrier and when set by the pattern 80 mechanism into line therewith for controlling the feeds to knit or not to knit, substantially as described.

8. In combination in a circular knitting machine, a plurality of feeds each including 85 knitting devices thereat, a plurality of selecting devices, one for each feed, each consisting of a member pivotally mounted to swing in a vertical plane, a carrier for the selecting devices, means for moving the carrier, pattern mechanism, means controlled thereby for setting the selecting devices in prescribed positions, and connections operated by the selecting devices as moved by the carrier for controlling the feeds to 90 knit or not to knit, said carrier and when set by the pattern mechanism into line therewith being arranged coaxially with the knitting head and turning about the axis thereof, substantially as described.

9. In combination in a circular knitting machine having a plurality of feeds disposed about the same at different points each including knitting devices, a series of selecting devices, one for each feed, means for giving travelling movement to the selecting devices, pattern means for setting the selecting means in selecting position in a prescribed order, connections extending from the selecting devices to the feeds to be operated by the selecting devices in their travelling movement, for controlling said feeds to knit or not to knit, each connection comprising a star wheel to be operated by one of the selecting devices, a cam operated by the star wheel, an arm operated by the cam, a rod operated by the arm, each feed when idle causing the needles to pass while holding their loops without knitting, substantially as described.

10. In combination in a circular knitting machine, having a plurality of feeds each including knitting devices thereat, a rotatable carrier member arranged coaxially of the knitting head, a reciprocating rod connected to said member for giving the same oscillating movement about the axis of the knitting head, a series of pivoted selecting devices mounted on the carrier and movable vertically about their pivots, means includ-

- ing pattern mechanism for moving the selecting members vertically about their pivots in a prescribed order, star wheels arranged to be contacted by the selecting devices in their travelling movement when the latter are in their selecting positions and connections leading from the star wheels for controlling the knitting at the feeds, substantially as described.
11. In combination with a circular knitting machine having a plurality of feeds each including knitting devices thereat, a movable carrier, a plurality of selecting devices pivotally mounted on the carrier, means for oscillating the carrier, pattern control means for setting the selecting devices in operative position in a prescribed order, star wheels, a fixed support for said star wheels, said fixed support furnishing the supporting means for the movable carrier, cams on the shafts of the star wheels, arms pivotally mounted and operated by the said cams, and radially extending rods operated by the pivoted arms for controlling the knitting at the several feeds, substantially as described.
12. In combination in a circular knitting machine having a plurality of feeds each including knitting devices thereat, a controlling mechanism arranged coaxially with the knitting head, said controlling means comprising a mechanically operated member and selecting devices carried thereby to have travelling movement therewith, connections extending from the controlling mechanism to the several feeds, said connections deriving their power from the mechanically operated member of the controlling mechanism and rendered effective or ineffective by the selecting devices, and pattern mechanism for controlling the selecting means in a prescribed order to hit or miss said connections in their travelling movement, substantially as described.
13. In combination with a circular knitting machine having a plurality of feeds each including knitting devices thereat, a take-up ring rotating with the rotary part of the knitting head, a vertical shaft, means carried by the rotary take-up ring for operating the vertical shaft, controlling means for the feeds comprising a member having travelling movement and operated from the said vertical shaft, connections leading from the said controlling means to the feeds to control the knitting, selecting devices connecting the said connections with or disconnecting them from the member operated by the vertical shaft, and pattern controlled means for setting the selecting devices in selecting position in a prescribed order.
14. In combination with a circular knitting machine having a plurality of feeds each including knitting devices thereat, connections leading to the said feeds to control the knitting, a power operated member at the axis of the knitting head, means for operating the said connections from the said power operated member, including selecting devices, a rotary take-up ring rotating with the rotary member of the knitting head, a connection operated by the rotary take-up ring for operating the power member of the controlling mechanism, and pattern means for controlling the selecting devices, to engage at prescribed times with the connections leading to the feeds substantially as described.
15. In combination with a circular knitting machine, having a plurality of feeds each including knitting devices thereat, controlling means therefor, including a set of operating connections, and means for selecting which of said connections will be operated, a rotary take-up ring moving in unison with the knitting head, and means carried thereby for actuating the said connections through the selecting means and pattern mechanism operated from the take-up ring and controlling the selecting means, substantially as described.
16. In combination with a circular knitting machine, having a plurality of feeds each including knitting devices thereat, controlling mechanism to determine when knitting is done or not at the said feeds, a rotary take-up plate, a cam thereon, connections operated by the cam for operating a part of said controlling mechanism, power transmitting connections leading from the controlling mechanism to the feeds, said controlling mechanism including a plurality of selecting devices for connecting in a prescribed order the transmitting connections with and disconnecting them from the said cam operated connections, pattern mechanism for setting the selecting elements in connecting position in a prescribed order, and a cam on the rotary take-up plate with connections therefrom for operating the pattern means, substantially as described.
17. In combination with a circular knitting machine having a plurality of feeds distributed at separated points about the same each including knitting devices thereat, a connection leading to each feed for determining whether or not knitting will take place there, controlling means for said connections including power operated driving means and selective devices for selecting in a prescribed order the particular connections which are to be operated by said driving means, and pattern mechanism for setting the selective devices in selecting position in a prescribed order, each feed when idle causing all of the needles to hold their loops without performing knitting actions at said idle feed, substantially as described.
18. In combination in a circular knitting machine having a plurality of feeds each in-

- cluding knitting devices thereat, star wheels with connections between the same and the feeds to cause knitting to be done, or cease, at said feeds, contact means travelling with the rotary member of the knitting head for operating the star wheels, means for adjusting said star wheels to bring different arms thereof into the plane of movement of the contact means, said adjusting means comprising a member arranged coaxially with the knitting head, selecting devices pivotally mounted on said member, means for giving said member a travelling movement, pattern mechanism with connections for setting said selecting devices in selecting position, and connections operated by the travelling movement of the selecting devices, when set, and connected with the star wheels, substantially as described.
19. In combination in a circular knitting machine having a plurality of feeds each including knitting devices thereat, star wheels with connections between the same and the feeds to cause knitting to be done, or cease, at said feeds, contact means travelling with the rotary member of the knitting head for operating the star wheels, means for adjusting said star wheels to bring different arms thereof into the plane of movement of the contact means, said adjusting means comprising a member arranged coaxially with the knitting head, selecting devices pivotally mounted on said member, means for giving said member a travelling movement, pattern mechanism with connections for setting said selecting devices in selecting position and connections operated by the travelling movement of the selecting devices, when set, and connected with the star wheels, said last mentioned connections including a star wheel operated by contact of the travelling selecting devices therewith, substantially as described.
20. In combination in a circular knitting machine having a plurality of spaced apart feeds with knitting devices at each feed, a controlling mechanism arranged coaxially with the knitting head and including a back and forth moving member, selecting devices movably mounted thereon to travel therewith, pattern mechanism for setting the selecting devices in effective position, connections operated by the travelling selecting devices when set by the pattern mechanism for controlling the knitting, a yarn cutter for severing the yarn when out of work, and means for operating said yarn cutter from the back and forth moving member.
21. In combination in a circular knitting machine having a plurality of spaced apart feeds with knitting devices at each feed, controlling mechanism for the knitting devices including an oscillating member and selective means thereon with connections therefrom to the knitting devices, pattern mechanism for setting the said devices to hit or miss said connections; a vertical post supporting said controlling mechanism, a yarn cutter, supported on said post, and means for operating the yarn cutter from the oscillating member, substantially as described.
22. In combination in a circular knitting machine having a plurality of feeds with knitting devices at each feed, connections leading to the knitting devices, selecting devices for selecting which of the connections are to be operated to change the knitting devices, a carrier on which said selecting devices are mounted, means for operating the carrier to give said selecting devices a travelling movement, pattern mechanism and mechanical connections between the same and the selecting devices for setting the same in position to strike and operate the appropriate set of connections during said travelling movement, or to miss them for changing the knitting devices to knit or not knit, substantially as described.
23. In combination in a circular knitting machine having a plurality of feeds with knitting devices at each feed, connections leading to the knitting devices, selecting devices for selecting which of the connections are to be operated to change the knitting devices, a carrier on which said selecting devices are movably mounted, means for operating the carrier to give said selecting devices a travelling movement, pattern mechanism and mechanical connections between the same and the selecting devices for setting the same in position to strike and operate the appropriate set of connections during said travelling movement or to miss them for changing the knitting devices to knit or not knit, said carrier being arranged coaxially with the knitting machine.
24. In combination in a knitting machine having a plurality of feeds with knitting devices at each feed, connections leading from a central head to the knitting devices for changing them to knit or not to knit, a carrier turning about the axis of the head and having mounted thereon selecting devices, one for each feed having up and down movement, mechanical connections to set the selecting devices by a downward movement in position to operate the appropriate set of connections in their travelling movement with the carrier, and pattern mechanism for selecting the appropriate set of the mechanical connections for setting the selecting devices in prescribed order, substantially as described.
25. In combination in a knitting machine having a plurality of feeds with knitting devices at each feed, selecting devices, one for each feed, a carrier on which the selecting devices are mounted, connections, one for each selecting device for changing the knitting devices to knit or not knit, said

connections being operable by the selecting devices in their travelling movement with the carrier when set in selecting position to contact therewith, means for operating the carrier, pattern mechanism, and a series of mechanical connections between the pattern mechanism and the selecting devices for setting the same in contacting position, said pattern mechanism being off-set to one side 10 of the knitting head with said connections reaching therefrom over said head to where the selecting devices are located, substantially as described.

26. In combination in a knitting machine 15 having a plurality of feeds with knitting devices at each feed, selecting devices, one for each feed, a carrier on which the selecting devices are mounted, connections, one for each selecting device for changing the 20 knitting devices to knit or not knit, said connections being operable by the selecting devices in their travelling movement with the carrier when set in selecting position to contact therewith, means for operating the 25 carrier, pattern mechanism, and a series of mechanical connections between the pattern mechanism and the selecting devices for setting the same in selecting position, said connections each consisting of a flexible member 30 and guiding means therefor.

27. In combination in a knitting machine having a plurality of feeds with knitting devices at each feed, selecting devices, one for each feed, a carrier on which the selecting 35 devices are mounted, connections, one for each selecting device for changing the knitting devices to knit or not knit, said connections being operable by the selecting devices in their travelling movement with the 40 carrier when set in selecting position to contact therewith, means for operating the carrier, pattern mechanism, and a series of mechanical connections between the pattern mechanism and the selecting devices for setting the same in selecting position, each of 45 said connections consisting of a flexible member movable longitudinally and a guide tube in which said flexible member works, substantially as described.

50 28. In combination with a circular knitting machine having a plurality of feeds with knitting devices at each feed to be set to knit or not to knit, an oscillatory carrier arranged coaxially above the knitting head, 55 selecting devices mounted on said carrier to travel therewith and having movement to be set into and out of contacting position on said carrier, pattern mechanism arranged to one side of the knitting head, a series of 60 mechanical connections extending from the pattern mechanism to the selecting devices for setting them in contacting position, star wheels contacted by the selecting devices when in contacting position, cams operated 65 by the star wheels, and connections operated

by the cams and extending to the knitting devices for shifting the same, substantially as described.

29. In combination with a circular knitting machine having a plurality of feeds 70 with knitting devices at each feed to be set to knit or not to knit, an oscillatory carrier arranged coaxially above the knitting head, selecting devices mounted on said carrier to travel therewith and having movement to 75 be set into and out of contacting position on said carrier, pattern mechanism arranged to one side of the knitting head, a series of mechanical connections extending from the pattern mechanism to the selecting devices 80 for setting them in contacting position, star wheels contacted by the selecting devices when in contacting position, cams operated by the star wheels, and connections operated by the cams and extending to the knitting 85 devices for shifting the same, said connections including star wheels, with means operated thereby for shifting the knitting devices to knit or not to knit, and a travelling contact for operating the last mentioned 90 star wheels, substantially as described.

30. In combination in a circular knitting machine, selecting means for controlling the knitting at the various feeds thereof comprising plates mounted to move up and 95 down, an oscillating carrier for said plates, connections operated by contact of the plates therewith when in one position but missed by said plates when the latter are in their other positions, said connections 100 when operated shifting the knitting devices to knit or not to knit, pattern mechanism off to one side of the knitting head and a series of mechanical connections extending therefrom to the plates extending up from 105 the pattern mechanism thence across to near the center of the machine and then down to the pivoted plates, substantially as described.

31. In combination in a circular knitting 110 machine, selecting means for controlling the knitting at the various feeds thereof, to knit or not to knit, pattern mechanism arranged off to one side of the machine, and a set of mechanical connections extending up from 115 the pattern mechanism, thence across to near the center of the machine and then down at their inner ends to the selecting devices to operate the same said inner ends having up and down movement, substantially 120 as described.

32. In combination in a circular knitting machine, means for controlling the knitting at the various feeds thereof, to knit or not to knit, pattern mechanism arranged off to 125 one side of the machine, and a set of mechanical connections extending up from the pattern mechanism, thence across to near the center of the machine and then down to the selecting devices to operate the same, said 130

- connections including flexible members, tubes in which they are guided the ends of the flexible members engaging respectively the selecting devices and the pattern means.
33. In combination in a knitting machine, a plurality of feeds each including knitting devices thereat, connections to each feed for setting the same to knit or not to knit, a carrier, devices thereon, for hitting or missing, said connections, a rock shaft, connections between said rock shaft and the said carrier for imparting movement thereto, pattern mechanism to set said devices in position to hit and operate the said connections, pawl and ratchet means for operating the pattern mechanism and an arm operated by the forward movement of the rock shaft for operating the pawl, of the pawl and ratchet mechanism, substantially as described.
34. In combination in a knitting machine having a plurality of feeds with knitting devices at each feed, including a needle raising cam, shiftable to operative or inoperative position, a series of star wheels, one for each feed, a connection between the star wheels and the shiftable needle raising cams, a contact member rotating with the machine for operating the star wheels and selector mechanism with pattern mechanism for controlling the same, said selector mechanism having connections for setting the star wheels in position to be operated by the travelling contact, substantially as described.
35. In combination in a circular knitting machine, having a plurality of spaced apart feeds each including knitting devices thereat, a movable carrier, a plurality of selecting devices movably mounted on the carrier, means for giving the carrier travelling movement, a support on which it moves, means for setting the selecting devices in selecting position in a prescribed order and connections extending from the selecting devices and hit or missed thereby for controlling the feeds to knit or not to knit, said connections including means mounted on the said support, and arranged to be operated by the travelling selector devices, substantially as described.
36. In combination in a circular knitting machine, having a plurality of feeds each including knitting devices thereat, a rotatable carrier member arranged coaxially of the knitting head, a plurality of selecting member arranged about the center of the carrier, and pivotally mounted, pattern mechanism for positioning the selector members by moving them about their pivots and means operated by the pivotally mounted selecting members when positioned for controlling the feeds when said members are set in selecting position said members having a hit or miss position relative to the last mentioned means.
37. In combination in a knitting machine, having a plurality of feeds with knitting devices at each feed including a needle raising cam shiftable to operative or inoperative position or to position to make the needle hold their loops without knitting, yarn guides, a series of star wheels rotatable about vertical axes, and shiftable to different levels, said star wheels having arms at different levels, means travelling with the rotary part of the machine for contacting with and operating the star wheels step by step, a cam member for each star wheel, a connection between each cam and the needle raising cam for controlling the latter, and means for moving the star wheels to different levels to locate its upper and lower arms in the path of the contacting means, substantially as described.
38. In combination in a knitting machine having a plurality of spaced apart feeds each including knitting devices thereat, means for rendering the feeds effective or ineffective to knit or not to knit, comprising a cam of each feed and a plurality of star wheels, one for each feed, arranged with their axes extending vertically, connections for setting the cams in different positions by the star wheels, said star wheels having arms at different levels, means on the rotary part of the machine for engaging and operating the star wheels step by step, and a movable support in which the shaft of the star wheel is mounted and means for moving said support, substantially as described.
39. In combination in a knitting machine for doing striping of the fabric, a plurality of feeds, each having a stationary yarn guide, and a yarn clamp, a yarn cutter at the axial center of the machine, a needle advancing cam at each feed with connections leading to each cam for adjusting said cams to an intermediate position to cease knitting while holding their loops, a central head, including an oscillating carrier, a plurality of members mounted thereon, one for each feed to be set in position to contact with and operate or miss the set of connections extending to the cam to which said member belongs, and pattern mechanism for operating said members in relation to the connections controlled thereby, substantially as described.
40. In combination in a knitting machine for doing striping of the fabric, a plurality of feeds, each having a stationary yarn guide, and a yarn clamp, a yarn cutter at the axial center of the machine, a needle advancing cam at each feed with connections leading to each cam for adjusting said cams to an intermediate position to cease knitting while holding their loops, a central head, including an oscillating carrier, a plurality of members mounted thereon, one for each feed, to be set in position to contact with

- and operate or miss the set of connections extending to the cam to which said member belongs, and pattern mechanism for operating said members in relation to the connections controlled thereby, said pattern mechanism including flexible connections leading to said members and guide tubes in which said connections slide, substantially as described.
41. In combination in a circular knitting machine, a single row of needles for making plain fabric, a ring having feeds disposed about the same at separated points, each including knitting devices thereat, a central head disposed coaxially of the open ring, devices mounted on the head, pattern mechanism controlling the selection and setting of the said devices, connections extending from the said devices outwardly to the feeds and power operated means for moving the selected devices when set by the pattern mechanism to drive the connections belonging thereto, leading to the feeds to render the feeds effective or ineffective in knitting.
42. In combination in a circular knitting machine a plurality of feeds disposed at separated points, about the same each including knitting devices thereat, devices disposed at separated points about the axial center of the machine to be selected to determine which of the feeds will knit and which will not knit, connections from said devices extending outwardly to the feeds, pattern mechanism controlling the selection and setting of the said devices, power driven means for operating the selected devices when set by the pattern mechanism, substantially as described.
43. In combination in a circular knitting machine, needles, rotary carrier means therefor, a plurality of feeds, spaced apart, around the machine each including knitting devices thereat, star wheels adjacent the feeds for rendering them operative or inoperative to knit or not to knit, contact means travelling with needle carrier for operating the star wheels, a connection for each feed for relatively adjusting the star wheels and contact means to hit or miss, a plurality of means to be selected for determining which of the said connections is to be operated for relatively setting the star wheels and contact means, a travelling carrier for said means, power operated connections for operating the carrier, and pattern mechanism for setting the means to hit or miss said connections, substantially as described.
44. In combination in a circular knitting machine, needles, rotary carrier means therefor, a plurality of feeds spaced apart around the machine each including knitting devices thereat, contact means travelling with the rotary carrier, contact devices hit or missed by said contact means for setting the feeds into or out of operative condition to knit or not to knit, mechanism arranged coaxially with the machine, including power transmitting devices to be selected for determining which of the contact devices will be hit by said contact means, pattern mechanism for selecting and setting the power transmitting devices and power operated means for rendering the selected power transmitting devices effective when set by said pattern mechanism.
45. In combination in a circular knitting machine, needles, supporting means in which they slide, a plurality of feeds spaced apart around the machine, including needle operating cams, and fixed yarn guide means, and mechanism for automatically controlling the performance or cessation of knitting at the feeds in a prescribed order for striping, said mechanism adjusting the needle advancing cams to cause the needles to knit by advancing them to take the yarn or not knit by advancing them only to an intermediate position, and when not knitting to cause all of the needles passing the cams of the idle feed to hold their loops, and pattern means for controlling said mechanism, any one, all, or various combinations of the feeds being effective, at one time, substantially as described.
46. In combination in a circular knitting machine, needles, rotary carrier means therefor, a plurality of feeds spaced apart around the machine and each having a yarn guide and a set of knitting cams, including a needle advancing cam, contact means on the rotary carrier, contact means for each feed connected with the needle advancing cam at said feed, and pattern controlled means for setting the contact means of the carrier and of the feeds relatively in and out of line with each other for setting the needle advancing cams in a prescribed order to render the feeds active or inactive, all of the needles passing an inactive feed holding their loops without knitting, substantially as described.
47. In combination in a circular knitting machine, needles, rotary carrier means therefor, a plurality of feeds spaced apart around the machine and each having a yarn guide and a set of knitting cams, including a needle advancing cam, contact means on the rotary carrier, contact means for each feed connected with the needle advancing cam at said feed, and pattern controlled means for setting the contact means of the carrier and of the feeds relatively in and out of line with each other for setting the needle advancing cams in a prescribed order to render the feeds active or inactive, all of the needles passing an inactive feed holding their loops without knitting, said contact means for the feeds comprising star wheels on vertical axes having arms in different horizontal planes, said star wheels being

moved by the pattern mechanism, to change their level.

48. In combination in a circular knitting machine, needles, a plurality of feeds spaced apart around the machine each including knitting devices thereat, a set of connections to each feed for rendering them active or inactive, to knit or not to knit, travelling means for operating the connections, pattern mechanism, and means operated by the pattern mechanism for setting the said connections to be operated by the means first mentioned, including flexible members movable longitudinally and guide tubes in which said flexible members slide, substantially as described.

49. In combination in a circular knitting machine, needles, a plurality of feeds spaced apart around the machine each including knitting devices thereat, a set of connections to each feed for rendering them active or inactive, travelling means for operating the connections, pattern mechanism and means operated by the pattern mechanism for setting the said connections to be operated by the means first mentioned, including flexible members movable longitudinally and guide tubes in which said flexible members slide, said flexible members and tubes having their inner ends disposed substantially vertically and by their elevated and lowered position, determining which feed is to be inactive and which active, substantially as described.

50. In combination in a circular knitting machine, needles, supporting means therefor, a plurality of feeds spaced apart around the machine each including knitting devices thereat, hit and miss devices, connections therefrom to the feeds for controlling them to be active or inactive to knit or not to knit, said hit and miss devices including members movable relatively up and down into and out of line, pattern means and connections operated thereby for controlling the hit and miss actions of the said devices, said connections including flexible members movable longitudinally and tubes in which said members move, the inner ends of said tubes and flexible members where they exert their control being disposed substantially vertically.

51. In combination in a circular knitting machine, having a plurality of feeds, each including knitting devices thereat, a rotary needle carrier, a star wheel adjacent each feed with means operated thereby for rendering the feed active or inactive to knit or not to knit, and for controlling all the needles passing the inactive feed to simply hold their loops without knitting, contact means travelling with the rotary needle carrier, for operating the star wheels, and means for setting the star wheels to different positions to be hit or missed by said

travelling contact means, said setting means including a star wheel, one for each feed with connections between said star wheels and the star wheels first mentioned, a travelling carrier, devices thereon for operating the star wheels of the setting means, when adjusted to hit the same, and pattern mechanism for setting the said devices in or out of line with the star wheels last mentioned, substantially as described. 75

52. In combination in a circular knitting machine, having a plurality of feeds, each including knitting devices thereat, a rotary needle carrier, a star wheel adjacent each feed with means operated thereby for rendering the feed active or inactive to knit or not to knit, and for controlling all the needles passing the inactive feed to simply hold their loops without knitting, contact means travelling with the rotary needle carrier for operating the star wheels, and means for setting the star wheels to different positions to be hit or missed by said travelling contact means, said setting means including a star wheel, one for each feed 80 with connections between said star wheels and the star wheels first mentioned, a travelling carrier, devices thereon for operating the star wheels of the setting means, when adjusted to hit the same, and pattern mechanism for setting the said devices in or out of line with the star wheels last mentioned, 85 said star wheels rotating about vertical axes. 90

53. In a circular knitting machine, a plurality of feeds each including knitting devices thereat, connections extending from points within the needle circle outwardly to said feeds to control the same to knit or not to knit, carrier means oscillating about the axis of the machine and having 100 a plurality of contact devices thereon to hit or miss their appropriate connections leading to the feed, and pattern mechanism for setting said devices in a prescribed order to hit their connections and thereby control 105 the feeds, substantially as described. 110

54. In a circular knitting machine, a plurality of feeds each including knitting devices thereat, connections extending from points within the needle circle outwardly 115 to said feeds to control the same to knit or not to knit, carrier means oscillating about the axis of the machine and having a plurality of contact devices thereon to hit or miss their appropriate connections leading to the feed, and pattern mechanism for setting said devices in a prescribed order to hit their connections and thereby control the feeds, and connections between said pattern mechanism and the said devices comprising flexible members and guide tubes therefor, substantially as described. 120 125

55. In combination in a circular knitting machine, a plurality of feeds each including knitting devices thereat, pattern mechanism, 130

- transmitting connections from said pattern mechanism extending to points within the needle circle, said connections including longitudinally movable flexible members and 5 guide tubes therefor, devices set by the movement of the inner ends of said flexible members, a carrier for said devices, and connections operated by the said devices as set by the pattern mechanism through said 10 flexible connections for controlling the feeds to knit or not to knit, substantially as described.
56. In combination in a circular knitting machine, a plurality of feeds each including knitting devices thereat, pattern mechanism, transmitting connections from said pattern mechanism extending up from the pattern mechanism then inwardly towards the axis of the machine and then downwardly, de- 15
- vices set by the movement of the inner ends 20 of said transmitting connections, a carrier for said devices and connections extending radially outward to the feeds operated by their respective devices when set to contact therewith, substantially as described. 25
57. In combination in a circular knitting machine, a plurality of feeds, a central head, a carrier oscillating on said head, contact devices on the carrier, star wheels on the central head to be operated by the said de- 30 vices, connections from the star wheels to the feeds for controlling the latter, and pattern mechanism for setting the devices to hit or miss the star wheels.
- In testimony whereof, we affix our signatures. 35

KENNETH HOWIE.

WILLIAM O. TAYLOR.
